SANDER ATTACHMENT FOR SHAPING MACHINES

Paul Peter Zwirek, New Orleans, La., assignor of one-half to New Orleans Furniture Manufacturing Company, New Orleans, La., a company of Louisiana.

Application July 19, 1951, Serial No. 237,548.

8 Claims. (Cl. 51—100)

1

The present invention relates to a wood shaping and finishing machine and more particularly to an improved sander attachment arranged to be associated with the machine.

An important object is to provide an attachment including a base on which is slidably mounted a longitudinally adjustable bar to which is connected a curved operating arm that supports a motor carrying a revoluble abradant member. A fluid operating piston is connected to said arm and the adjustable bar, so as to provide means for normally urging and maintaining the abradant member in engagement with the curves or design of the work to impart a finished smooth surface thereto and thus eliminates hand sanding.

Other objects and advantages of the invention will become apparent from the following description when taken in conjunction with the accompanying claims and drawings.

Referring to the drawings in which is shown a preferred embodiment of the invention:

Figure 1 is a detail plan view of the improved sander attachment shown associated with a shaping machine and the work.

Figure 2 is an enlarged detail sectional view taken substantially along the line 2—2 of Figure 1.

Figure 3 is a sectional view taken substantially along the line 3—3 of Figure 1.

Figure 4 is a sectional view taken substantially along the line 4—4 of Figure 1.

Figure 5 is a sectional view taken substantially along the line 5—5 of Figure 1.

Figure 6 is a detail plan view showing means for moving the guide wheel and the abradant member out of engagement with the work.

Figure 7 is a detail side view of the base for supporting the fluid cylinder and its associated parts.

Figure 8 is a sectional view taken substantially along the line 8—8 of Figure 1.

Figure 9 is a detail perspective view of the means for connecting the fluid cylinder to the adjustable slide on the base, and

Figure 10 is a detail perspective of a part of the front end of the base.

Referring to the drawings, 10 (Fig. 3) indicates a pattern or jack which is suitably clamped or connected to the top of a shaper table, not shown, and which supports the work 11, such as a piece of furniture, that previously has been cut to the desired shape. In order to impart a smooth sanded finish to the work after it has been shaped by the cutter, there is provided a sander attach-

2

ment which includes a fixed base or supporting member 12 (Fig. 4) having detachably mounted thereon a flat metal plate 13 by the bolts 14 so as to constitute a bed on which are detachably secured the spaced side pieces 15 by the clamping screws 16. The inside surfaces of these pieces are inclined or cut at an angle as at 17 so as to engage complementary formed tapered sides 18 of a longitudinally slidable metal member or bar 19 (Fig. 4). Thus, it will be seen that the side pieces 15 coact with the base 13 to provide a guideway of dove-tail shape for receiving the slidable member 19. It will be seen that upon releasing of the bolts 16, the member 19 may be adjusted longitudinally relative to the base 13 and upon tightening-up of the bolts 16, the pieces 15 are forced into clamping engagement with the base and the tapered sides 18 of the member 19 so as to maintain the latter in an adjusted position. The member 19 adjacent its inner end has a plate 20 (Fig. 1) secured thereto by the bolts 21 and carries an upwardly extending stud or pin 22 on which is clamped a split housing 23 by the threaded bolts 24. The housing 23 has extending laterally and outwardly therefrom a reinforcing web 25 and an integral strap 26 (Fig. 9) that abuts against the inner end of a fluid cylinder 27. Threaded retaining rods 28 extend through openings in the plate 26 and the chamber head 29 of the cylinder 27 so as to maintain the cylinder in fixed position when the nuts 30 are secured to the ends of the rods 28. A reciprocating piston 31 extends outwardly from the chamber 29 of the cylinder 27 and also through a guide plate 32 that projects laterally from the side of the base 13. A stop member 33 is axially adjustable on a rod 34 which is connected at one end to a slideable tubular boss 35 on the plate 32 and at its opposite end extends loosely through the lug 36 on the head 29, so as to be movable relative thereto. An extension plate 37 projects from the plate 26 and may be secured thereto by the bolts 28 and nuts 30 (Fig. 1). A complementary plate 38 parallel with the plate 37 extends outwardly from the plate 32 and may be secured thereto by the bolts 32 (Fig. 10). A rod 39 extends through the plates 37 and 38 and carries a sleeve 40 between which and the plate 38 is confined a tension spring 41. The outer end of the rod 39 is threaded to receive a nut 42 and also carries a collar 43 between which and the plate 38 is positioned a compression spring 44.

The adjustable slidable member 19 is of such a length as to extend beyond the opposite ends

of the base 12 and at its inner end or adjacent the work 11, is pivotally connected to a motor supporting arm 45 as at 46 (Fig. 1). A plate or strap 47 has a lug 48 projecting rearwardly therefrom and overlaps a strap or extension 31' connected to the outer end of the piston 31. The lug 48 may be pivotally connected to the strap 31' by the bolt 49 and the cotter pin 49', so that axial movement of the piston 31 imparts a swinging movement to the arm 45 and its associated parts, about the pin 46. The opposite end of the plate 47 overlaps the arm 45 and may be secured thereto by the spaced clamping bolts 50. Thus, it will be seen that the plate 47 constitutes an extension of the arm 45 so as to connect the latter both to the slidable member 19 and the piston 31 of the cylinder 27. Manifestly, the arm 45 and the plate 47 may be made in one piece. The supporting arm or member 45 extends laterally from the side of the base 13 so as to be positioned adjacent the work 11 and is preferably bent or curved as at 51 at an angle of substantially 45°, and terminates in an end portion 52, to the underside of which is secured a metal base member 53 by the bolts 54 (Fig. 2). The underside of the base 53 is provided with the depending spaced side pieces 55 and 55', the piece 55' being detachably connected to the base 53 and the piece 55 preferably integrally extending therefrom. The spaced sides 55 and 55' coat with the base 53 to provide a substantially dove-tail shaped guideway which slidably receives a complementary formed elongated plate 56 (Fig. 3), to the outer end of which is revolubly mounted a wheel 57 arranged to contact with the side of the pattern or support for the work 11. An adjusting screw 58 extends through a depending threaded boss 59 of the plate 53, so as to engage the arm 56 and regulate the longitudinal movement of the wheel 57 relative to the base 53. The rod 58 at its outer end may be formed with a knurled operating head 58'. Spaced set screws 60 (Fig. 2) extend through the detachable piece 55', so as to provide means for clamping the plate 56 in a predetermined longitudinally adjusted position. An L-shaped bracket 61 has a horizontal arm 62 (Fig. 3) secured by the bolts 64 to the adjacent curved end of the supporting arm 45, and the vertical arm 65 of the bracket has an elongated slot 66 (Fig. 2) for slidably receiving a locking bolt 67 for adjustably connecting a supporting plate 68 thereto. An electric motor 69 is connected to the plate 68 by the bolts 69' so as to be supported and be movable therewith. The motor 69 has extending downwardly and centrally therefrom, a rotatable shaft 71 which is detachably connected to a conventional or well-known sanding device including a drum 72 having a centrally disposed sleeve 73 into which the shaft 71 extends and is adjustably secured by the set screws 74. To the outer periphery of the metal drum or disc 72 is connected a suitable abradant, such as sandpaper, emery or the like 75, which is arranged to be brought into finishing engagement with the side of the work 11 after it has been shaped by the cutter. When it is desired to temporarily suspend the sanding operation, a protuberance in the form of a semi-circular wooden button or the like 76 may be detachably connected to the side of the pattern or jack 10 (Fig. 6), so as to be positioned in the path of the roller 57 in order to move the abradant member 75 away from the work 11.

The side pieces 15, while shown separate from the base 13, may be integrally formed therewith

in order to provide the dove-tail guideway. The longitudinally adjustable bed member 19 may be provided with threaded openings for receiving set screws 77 (Fig. 1) that coat with the clamping screws 16 for maintaining the bed 19 fixed in its longitudinally adjusted position. Additionally, oil cups 78 may be connected to the side pieces 15 so as to lubricate the movable surfaces of the member 19 which contact the pieces 15. The motor 69 is connected by the insulated cable or wire 29 to a source of electrical energy for causing the rotation of the abradant wheel 75.

In operation, assuming that the work 11, such as a piece of furniture, has been shaped by the cutter to form the desired pattern, the sander or abradant attachment is then moved to the position as shown in Figure 1. The bed 19 is first longitudinally adjusted to properly position the abradant 75 in engagement with the side of the work and the bed 19 is clamped in a fixed position by tightening-up of the set screws 16 and 77. The longitudinal displacement of the bed 19 simultaneously moves the hydraulic cylinder 27 which is connected thereto by the web 25 and the plate 26. At the same time, the plate 56 is longitudinally adjusted so as to properly position the wheel 57 in contact with the pattern or jack 10 by the manual actuation of the rod 58, and is clamped in its adjusted position by tightening-up of the set screws 60 which forces the removable piece 55' to be brought into tight frictional engagement with the adjacent tapered face of the bed 56. Air or other fluid is then introduced under pressure through the pipes 78 into the head of the cylinder 29, so as to force the piston 31 and plates 32 and 38 rearwardly or away from the work 11 and against the tension of the compression spring 41. The rearward movement of the piston 31 is limited by the engagement of boss 35 with the adjustable strap 33 (Fig. 8). The inward movement of the piston 31 simultaneously causes the arm 45 to swing about its pivot 46 so as to yieldably urge the abradant surface 75, now being rotated by the motor 69, into sanding contact with the rough design previously cut by the shaper on the work 11. It will be seen that the sander 75 fits closely into the curves of the design and are held in close yielding engagement therewith by the action of the compressed air in the cylinder 29 and the tension spring 39. Thus, the rough cut made by the sander is properly sanded and given a smooth and uniform finish, without requiring the manual handling of the material or work 11.

When the air pressure is released from the cylinder head 29, the compression spring 44 tends to move the piston 31 outwardly towards the work and the abradant 75 away therefrom. In this connection, it might be mentioned that the tension of the sanding device is regulated by the air pressure admitted into the cylinder 27 and also by the tension applied to the spring 39 and the compression spring 44 disposed on opposite sides of the plate 38 (Fig. 1). The tension spring 41 may be considered as applying a backward or rearward pressure to the piston 31 and the operating arm 45, while the compression spring 44 tends to apply a forward pressure which may be adjusted or regulated by the nut 42. Thus, it will be seen that the longitudinal adjustment of the slidable member 19 acts to regulate the depth of force exerted by the sanding wheel or abradant 75 against the work 11. As the piston 31 is slidably mounted in the cylinder 27 and also operatively connected to the arm 45, it is free

to move back and forth in connection with the pressure exerted against the work 11 by the abradant 75. The guide roller 57 is longitudinally adjusted so as to contact with the pattern or jack 10 in order to control the depth of cut or sanding action of the abradant 75. As the guide roller 57 is adjustable at the rear of the base 56 by the bolts 58, it does not bear heavily against the pattern 10, so that the sanding drum 72 presses more heavily against the work than the roller 57 against the pattern. Moreover, when the sliding plate 56 is adjusted further forward in the plate 53, it tends to hold the sanding surface 75 away from the work, so that the pressure exerted on the drum 72 is reduced and consequently the cut made by the sandpaper 75 is less and lighter. When it is desired that the sandpaper 75 not be brought into engagement with the work without cutting off the motor 69, or if it is desired to stop the sander at a certain point in the finished material, the protuberance 76 may be nailed or otherwise connected to the pattern (Fig. 10) so as to move the roller 57 and the sander away from the work, as shown in dotted lines in Figure 6.

Thus, it will be seen that a simple, efficient and positive sander attachment is provided which can be readily associated with a shaper table or the like in order to impart a smooth finish to the work after the same has been shaped by a wood cutter or the like. Additionally, pneumatic means are provided for yieldably maintaining and guiding the sanding wheel in proper position and for effecting ready adjustment of the parts, so that the attachment may be conveniently used for providing a smooth sanded finish to various types and shapes of patterns used in manufacturing furniture and other articles made of wood or the like, so that the material is at once ready for assembling without requiring manual handling for sanding the same.

The form of the invention shown is merely illustrative of a preferred embodiment and it is understood that such changes may be made as come within the scope of the following claims.

I claim:

1. In combination with a work carrier, a sander attachment for acting upon the work, said attachment including a base, an operating arm pivotally connected to the base and extending transversely thereof, said arm having a curved end portion, a motor mounted on said end portion, an abradant member operatively connected to said motor and arranged to be moved into sanding engagement with the work, a guide wheel adjustably mounted on said arm and arranged to engage the work carrier for maintaining the abradant wheel in proper position relative to the work, fluid pressure means connected to said operating arm adjacent the other end thereof for swinging the arm about its pivot in order to move the abradant member in engagement with the work, and spring means operable when the fluid pressure means is released for moving the abradant member away from the work.

2. In combination with a work carrier, a sander attachment for acting upon the work, said attachment including a base, a longitudinally movable member adjustably mounted on said base, an operating arm pivotally connected to said movable member and extending laterally from one side thereof, said arm terminating at one end in a curved portion, a motor mounted

on said curved portion, an abradant member operatively connected to said motor, a hydraulic cylinder connected to said movable member so as to be longitudinally displaceable therewith, said cylinder having a piston connected to said operating arm so as to cause the same to be swung about its pivot in order to move the abradant member in engagement with the work, and spring means for moving the operating arm and the abradant member away from the work.

3. In combination with a work carrier, a sander attachment for acting upon the work, said attachment including a base, a longitudinally movable member adjustably mounted on said base, a fluid pressure cylinder spaced from said movable member and having a reciprocating plunger, means connecting said member to said cylinder so as to be movable therewith, a supporting arm extending transversely from one end of said movable member, means pivotally connecting said supporting arm to said movable member, means operatively connecting said plunger to said supporting arm for swinging the same about its pivotal connection with said member, a fixed guideway connected to the opposite end of said supporting arm, a bar movably mounted on said guideway, a motor mounted on said bar so as to be movable therewith, a rotary abradant member operatively connected to the motor and arranged to contact the work to impart a finished surface thereto, and means arranged to engage the carrier for controlling the position of the abradant relative to the work during the operation of the machine.

4. In combination with a work carrier as called for in claim 3 in which means are provided for introducing fluid under pressure into said cylinder to move and maintain the abradant member in engagement with the work, and means are also provided when the fluid pressure is released in the cylinder for moving the abradant member away from the work.

5. An attachment of the class described including a base, a member slidable on the base, an operating arm extending transversely of said base and connected to said member, a fluid pressure cylinder, means connecting said cylinder to said member so as to be movable therewith, means for clamping said member in an adjusted position, a guide plate, said cylinder having a piston extending outwardly therefrom and through said guide plate, means connecting said piston to said operating arm, means for introducing fluid under pressure into said cylinder for moving the piston and said arm in one direction, spring means connected to said base and positioned on one side of said guide plate for coacting with said piston to move said arm, and a tension spring operatively connected to said piston and positioned on the opposite side of said guide plate for moving the same and said arm in an opposite direction when the fluid pressure to the cylinder is withdrawn.

6. An attachment as called for in claim 5 in which the clamping means includes spaced longitudinally disposed pieces having inclined sides arranged to engage complementary sides on said member, and means for detachably connecting said pieces to the base to firmly maintain said member in a fixed position.

7. In combination with a work carrier, a sander attachment for acting upon the work, said attachment including a base, an operating arm pivotally connected to the base and extending laterally therefrom, a revolute abradant member connected to said arm, means operatively

connected to said arm for moving the abradant member about its pivot and in engagement with the work, means for moving the abradant member away from the work, a guide roller for maintaining the abradant in proper operative position relative to the work, and a detachable protuberance connected to the work carrier and positioned in the path of said roller for moving the abradant out of engagement with the work.

8. In combination with a work carrier, a sander attachment for acting upon the work, said attachment including a base, a longitudinally movable member adjustably mounted on said base, an operating arm pivotally connected to said movable member and extending laterally from one side thereof, a revolvable abradant member connected to said arm and movable therewith for engagement with the work, fluid pressure means connected to said longitudinally movable member

and operatively associated with said arm so as to cause the same to be swung about its pivot in order to move the abradant member into engagement with the work, and means for moving the arm and abradant member away from the work.
